UNITED STATES PATENT OFFICE.

AMOS HENRY MATTHEW AND JESSIE BERT PROUTY, OF COLVILLE, WASHINGTON.

SAFETY DEVICE FOR SHIPS.

1,102,533.

Specification of Letters Patent.

Patented July 7, 1914.

Application filed June 6, 1913. Serial No. 772,062.

To all whom it may concern:

Be it known that we, AMOS H. MATTHEW and JESSIE B. PROUTY, citizens of the United States, and residents of Colville, in the county of Stevens and State of Washington, have invented a new and Improved Safety Device for Ships, of which the following is a full, clear, and exact description.

Our invention relates to brake wings carried by the vessel, to normally lie close against the sides thereof, and adapted to swing outward to impede the movement of the vessel.

The invention comprises a novel means for controlling the wings, to release and position them for braking action, and to fold them into inoperative positions. Use is made of a drive shaft and means to draw in the wings by the movement of the shaft, and a wing-releasing mechanism actuated by compressed air. Provision is made for receiving the compressed air from any conveniently located compressor or pump, there being manually-controlled means to cause the compressed air to release the wings; also, to release the wings automatically by the impact of the vessel against an under water obstruction, fisher rams or pilot plungers are provided, projecting beyond the bow of the vessel and so arranged that their forced rearward movement under the impact will serve to establish connections and apply a pressure to release the wings.

The distinguishing features of our invention and the important structural elements characterizing the practical embodiment which is illustrated as an example of means for carrying out the invention, will be more particularly explained in the specific description hereinafter to be given.

Reference is to be had to the accompanying drawings forming a part of this specification, in which similar characters of reference indicate corresponding parts in all the views.

Figure 1 is a partial plan view of a vessel equipped with our invention; Fig. 2 is a partial side elevation thereof; Fig. 3 is a cross section on a larger scale; Fig. 4 is a detail in horizontal section, on the line 4-4 of Fig. 3; Fig. 5 is a sectional plan view on the line 5-5 of Fig. 3; Fig. 6 is a detail in vertical section showing the operating ropes for drawing the wings into closed position; and Fig. 7 is a detail sectional view showing the plunger and presser rod for releas-

ing the wings to permit their outward movement.

In constructing our invention in accordance with the particular form illustrated as an example, series of wings 10 are suitably hinged at their rear vertical edges to the sides of the vessel 11. Within the vessel compressed air pipes are arranged as herein-after explained, and adapted to receive a supply of compressed air from a pipe 12 connected in practice with any pump or compressor (not shown), the compressed air serving to release the wings 10, and cause them to receive an initial outward impulse to assume a slight angle to the vessel and cause them to be swung to the full open position under the pressure of the water. Means are provided to draw in the wings, said means being actuated from a drive shaft 13 turning in suitable bearings 13^a. For each wing 10 a pusher rod 14 is provided, extending outwardly through the side of the vessel, and is carried by a plunger 15 movable in a cylinder 16, to which leads a branch pipe 17 from a vertical manifold 18, the respective manifolds being connected with supply pipes 19 to deliver compressed air at the back of the plungers 15.

Communicating with the pipe 19 which extends transversely of the vessel, are elbow pipes 20 that are connected by their arms 21 with a branch 22 leading from a standpipe 23, which has connection with the pipe 12 from the source of compressed air supply (see Fig. 5).

By the described pipe connections it will be seen that air, being maintained by reason of the pipe 12 in the standpipe 23, will be delivered laterally through the pipes 19 to the manifolds 18 behind the several plungers 15, to force the plungers and the pusher rods 14 outward to give an initial outward movement to the several wings. As the mechanism is the same at each side of the vessel, it will be sufficient to describe one set of mechanism only.

In order to provide for the automatic forcing outward of the wings, by impact against a submerged obstruction, plungers or rams 24 are provided in cylinders 25 that communicate at their rear ends with the standpipe 23. The plungers 24 extend forwardly and project beyond the bow of the vessel. In case the lowermost plunger 24 be broken by the greater likelihood of its encountering obstructions, owing to its

depth, the lower end of the standpipe 23 may be closed by a valve 23^a, which may have a handle 23^b, indicated in dotted lines in Figs. 3 and 4. Upon the plungers 24 contacting with an obstruction, they will be forced rearwardly, and in order that the increased pressure produced in the pipe system by the rearward movement of the plungers may automatically force out the plungers 15, there is provided a connection 20^a leading rearwardly from the branch 22 of the standpipe, the said connection 20^a being in communication with the transverse pipes 19.

15 Communication between the pipe connection 20^a and the pipes 20 is controlled by a plug valve 29 movable axially of the said pipe connection and extending across the pipe 19 into a rearward extension 26 in axial alignment with the connection 20^a. A rearward movement of the plug valve 29, the forward end of which is tapered as at 29^a, will permit air to be forced rearwardly through the connection 20^a into the pipe 19, 25 the latter branching laterally in opposite directions to the mechanism at the opposite sides of the vessel. A branch pipe 12^a establishes communication between the rearward pipe extension 26 and the initial supply pipe 12, so that the said rearward extension is subject to any excessive increase 30 of pressure in the initial supply pipe. A safety valve 27, of any known form, here shown as under control of a weighted arm 27^a, is provided in the rearward extension 26, and there may be a pressure gage 28 also provided if desired. A pressure gage 28^a may also be provided on the standpipe 23; thus there will be a gage in front of the plug 40 valve 29, and one in the rear.

In the elbow pipes 20 valves 30 are provided, of the rotary type, a partial turn of the valve serving to let air pass into the pipes 19, or to cut off the supply, if desired, 45 and in order to turn the said valves from the drive shaft 13, we mount on the latter friction disks 33, adapted to rotate with said drive shaft and also to slide thereon. The valves 30 have a wheel 30^a adapted to be 50 frictionally driven by the friction disks 33, and are formed with a flat side 30^b, so that they shall receive only a partial rotation (see Fig. 5).

To shift the disks 33 into and out of engagement with the wheels or disks 30^a of the valves, shifting yokes 34 are provided on the hubs of the disks 33 and adapted to be thrown by levers 35. The disks 33 turn the valves in one direction, say to open the 60 valve, and disks 36 on the drive shaft 13 at the opposite side of the valves 30, serve to give a reverse movement to the valves, the disks 36 being slidably by shifting yokes 37 controlled by levers 38.

65 Exhaust valves 31 to exhaust the air pres-

sure from the pipes 19 are provided in exhaust pipes 32, the said valves being provided with disks or wheels 31^a similar to the disks 30^a and adapted to be turned in one direction by friction disks 39 and in the opposite direction by friction disks 39^a on the drive shaft 13. The disk 39 is integral with and movable with the disk 36, and the yoke 37 has a connection 37^a with the yoke 37^b for shifting the disk 39^a.

The levers 35 may be thrown directly, or any suitable connection, as indicated at 41, may lead to the pilot house (not shown), or any other desired part of the vessel.

At the upper end of the standpipe 23, an exhaust outlet 42 is provided, commanded by a piston valve 43 in connection with a weighted arm 44, so that excessive pressure in said standpipe may be relieved by said valve 43. To manually open the valve 44, we provide a vertical rod 45 in threaded engagement at its upper end with a bracket 46 and guided also, if desired, in a second bracket 46 below, the said rod having a friction disk 47 adapted to be turned by friction disks 48 on the drive shaft 13. A shifting yoke 49 having a lever 50 may be employed to throw a disk 48 into driving engagement with the disk 47, for turning the screw rod 45 in a direction to raise the arm 44 and shift the valve 43, to open the exhaust pipe 42.

Referring particularly to Fig. 3, a pawl 51 engages a crown ratchet wheel 52 on a vertical shaft 53, having drums 54, winding on which are series of cables 55 that lead outward through the side of the vessel, as illustrated in detail in Fig. 6, to a connection with the wings 10. On the drive shaft 13 is a friction wheel 56 adapted to be moved longitudinally by a shifting lever 57, to bring the friction wheel into contact with the under side of the crown ratchet 52, for turning the shaft 53 and drawing the wings inward close against the vessel. Normally the pawl 51 holds the shaft 53 against turning, and in order to disengage the pawl and permit the wings to swing outward upon receiving the initial movement from the pusher rods 14, the said pawl 51 is provided with an arm 51^a which is adapted to be thrown to rock the pawl and disengage the ratchet by contact of a pusher rod 58 on a plunger 59, which is movable in a cylinder 60 and extends also into the end of the pipe 19 which is in axial alignment with said cylinder, as shown in Fig. 7. The arrangement is such that upon compressed air being admitted into the pipes 19, it will simultaneously force outward the plunger 59, to release the pawl 51 and the plungers 15 to give an outward initial movement to the wings 10.

Automatic friction brakes for the drums 54 are provided as follows: On the shaft 53

are coiled springs 70, one end of each spring abutting a collar 71 adjacent to one end of the drum, the opposite end of the spring abutting a cross-head 72 threaded onto the shaft 53, which engages guides 73; thus when the shaft turns by the unwinding of the cables 55, the cross-heads 72 will be moved against the springs 70 and cause the springs to press the brake collars 71 against the drums 54.

It will thus be observed that the system provides for the automatic release of the wings as well as for their manual release, so that they may be brought into action by the pilot rams coming in contact with an obstruction, or at the will of the ship's officers.

In order that the openings through which the cables pass shall be effectively closed both when the wings are in the folded and in the outward position, each hole is provided with a bushing 61 (see Fig. 6) which may flare as at 62, 63, at the exterior and interior of the vessel, and on the cable 55 buttons 65 and 66 are provided at the interior and exterior of the vessel, the button 65 at the interior being adapted to seat on the inner seat 62, when the wing is swung outward; similarly the button 66 at the exterior may seat on an auxiliary seat 64, at the flared end thereof, the described arrangement being one form of devices for the purpose.

The described construction is to be understood as affording a practical means for carrying our invention into effect, and we would state in conclusion that we do not limit ourselves to the mechanical details herein illustrated, since manifestly the same can be considerably varied without departure from the spirit of the invention.

Having thus described our invention, we claim as new and desire to secure by Letters Patent:

1. A safety device for marine vessels, comprising hinged wings on the exterior of the vessel, cables connected with said wings and leading to the interior of the vessel, drums for said cables, a shaft on which said drums are mounted means to hold said shaft against turning, and a fluid-actuated device for releasing said means.

2. In a safety device for marine vessels, brake wings on the exterior of the vessel hinged at their rear edges, cables attached to said wings and extending to the interior of the said vessel, winding drums for said cables, a shaft for actuating said drums, a drive shaft, means for making and breaking the driving connection between the drive shaft and the drum shaft, a device normally holding the drum shaft against turning, and fluid-controlled means for releasing said device.

3. In a safety device for marine vessels, brake wings hinged at their rear edges, cables connected with the wings and extend-

ing to the interior of the vessel, drums for winding said cables, an actuating shaft for said drums, a drive shaft, means to establish driving connection between the drive shaft and the drum shaft for winding the cables on the drums, a device normally holding the drum shaft against turning in a direction to unwind the cables, a fluid-controlled device to give an initial outward movement to the wings, a fluid-controlled means for releasing the device that holds the drum shaft, and means to supply a fluid under pressure simultaneously to both of said fluid-controlled means.

4. In a safety device for marine vessels, a series of brake wings on the exterior of the vessel, plungers carrying members to give an initial outward movement to the wings, cylinders in which said plungers have movement, a manifold communicating with said cylinders, an air pipe leading to said manifold, a standpipe, valve connections between the standpipe and the said air pipe, forwardly disposed cylinders communicating with the standpipe and rams operating in said forwardly disposed cylinders and extending forwardly beyond the bow of the vessel.

5. In a safety device for marine vessels, a series of brake wings on the exterior of the vessel, pilot rams projecting forwardly beyond the bow of the vessel, cylinders in which said rams are movable, a fluid-controlled means for giving an initial outward movement to the wings, and connections between said cylinders and said fluid-controlled means to cause said rams, when moving rearwardly in their cylinders, to exert air pressure against said fluid-controlled means.

6. In a safety device for marine vessels, a series of exterior brake wings hinged at their rear edges, cables extending from said brake wings to the interior of the vessel, series of winding drums for said cables, a shaft for actuating said drums, a ratchet disk on said shaft, a pawl adapted to engage said ratchet disk and hold the drum shaft against turning to unwind the cables, a fluid-controlled release device for said pawl, a pipe for supplying a fluid under pressure to the said release device, a drive shaft, a driving element on said drive shaft movable into engagement with the ratchet disk to turn the drum shaft in a direction to wind the cables, a valve controlling the supply of fluid to the said pipe, an exhaust from the said pipe, a valve for controlling said exhaust, and actuating means slidably on the drive shaft and rotatable therewith to reversely operate the said valves.

7. In a safety device for marine vessels, brake wings on the exterior of the vessel, at each side, and hinged to swing toward and from the vessel, means to hold the wings in

the inner position, fluid-controlled means to release the wings and cause them to swing outward, and means for supplying compressed air to said fluid-controlled means, 5 said last-mentioned means consisting of a pipe having communication with the fluid-controlled means at each side of the vessel, and ranging transversely of the latter, an initial supply pipe adapted to receive compressed air from a source of supply, a stand- 10 pipe to which said supply pipe leads, valved pipe connections extending from said standpipe to the transverse pipe leading to the fluid-controlled means, a pipe extending 15 from said transverse pipe at the opposite side from the connection with the standpipe and in axial alinement with said connection, and a piston valve in the last mentioned pipe connection at the junction of the same with 20 the transverse pipe.

8. In a safety device for marine vessels, brake wings on the exterior of the vessel hinged at the rear edges to swing toward and from the vessel, cables connected with 25 the wings and leading to the interior of the

vessel, drums to which the cables lead, said cables carrying buttons on the interior of the vessel and at the exterior thereof, there being seats on the hull of the vessel, at the interior and exterior, to receive said buttons 30 to close the passages through which the cables lead.

9. In a safety device for marine vessels, brake wings on the exterior of the vessel mounted to swing inward and outward, 35 cables connected with the wings and leading to the interior of the vessel, drums on which the cables wind, a shaft on which the drums are mounted, brakes for the drums, and means operative by the turning of the shaft 40 in response to the unwinding of the cables for applying the brakes to the drums.

In testimony whereof we have signed our names to this specification in the presence of two subscribing witnesses.

AMOS HENRY MATTHEW.

JESSIE BERT PROUTY.

Witnesses.
